INJECTION VALVE FOR INTERNAL
COMBUSTION ENGINES

Ernst Wirtzen, Chester, Pa.

Original application August 31, 1936, Serial No. 98,775. Divided and this application October 14, 1938, Serial No. 235,070

2 Claims. (Cl. 299—107.2)

My invention relates to injection valves for internal combustion engines, and is especially adapted for application to two-cycle engines including those of the Diesel type.

5 The principal object of my invention is to provide an injection valve that will utilize the air pressure produced in the cylinder on the operation of the engine to thereby simplify operation of the valve to take the place of the 10 complicated and expensive fuel injection pump and injection valve commonly employed in engines of this general character.

With this principal object in view my invention contemplates a construction of injection valve 15 to include a piston working under spring pressure at the inner end of an opening through the wall of the engine-cylinder, in connection with a spring-actuated needle-valve controlling the opening through the nozzle from which the fuel 20 is discharged into the engine-cylinder for a co-operation depending upon the pressure of air on the upstroke of the engine-piston; all as hereinafter fully described and more specifically set forth in the appended claims.

25 In the drawing:

Figure 1 is a sectional view through an injection valve constructed in accordance with my invention, showing the normal position of the valve-piston and co-acting needle-valve.

30 Fig. 2 is a similar view showing the position of the co-operating elements of the valve under air pressure in the engine-cylinder.

Fig. 3 is a fragmental view illustrating the 35 position of the valve-piston and needle-valve in discharging the fuel oil from the nozzle, and

Fig. 4 is a diagrammatic view or graph to illustrate the operation of the injection valve.

The injection valve, in accordance with my invention, is illustrated as being located in an opening, 10, through a wall of the engine cylinder, 10a instead of an independent casing, the operating parts including as essential elements a spring-actuated valve-piston provided with a discharge nozzle at the lower end thereof, and co-operating with a spring-actuated needle-valve adapted to supply the fuel mixture to a valve chamber communicating with a nozzle discharging into the combustion chamber of the engine cylinder.

50 The valve-piston, 11, works in a bushing 12 fixed in the lower end of the opening 10 and is actuated in one direction, or towards the engine-cylinder, by a spring 13 interposed between the piston and a cap 14 closing the outer 55 end of the opening, that end of the spring engaging the piston being preferably seated in an annular recess 15 surrounding a tubular projection 16 projecting upwardly from the center of the piston with the opening through the projection communicating at its lower end with a

valve chamber 17 from which a nozzle 18 projects through the inner end of the piston. The discharge of fuel oil through the nozzle is controlled by a reciprocating valve rod 19 reduced in size and tapered at its lower end to form a 5 plug seating within a corresponding opening in the nozzle, after the manner of a needle valve, and this valve rod is hollow from the top to near the lower end thereof to provide a passage for the fuel oil, with openings or ports 20 extending through the opposite sides of the rod for discharging the fuel oil into the valve chamber when the ports are exposed below a sleeve 21 in which the valve rod works. For augmenting the discharge of oil from the hollow valve 15 rod into the valve chamber said rod is provided with a circumferential recess 22, with which the openings 20 communicate, and so as not to interfere with movement of the valve-piston in the recess in the cylinder there is a vent 23 extending from the upper part of said recess through the cylinder wall to the atmosphere.

The sleeve housing the valve rod extends through the cap 14 and into the tubular projection 16 of the valve piston, and below the 25 lower end of this sleeve the piston is hollowed out to provide the valve chamber hereinbefore referred to.

The operation of the valve rod in opening and closing the nozzle for discharging the fuel oil 30 into the engine cylinder is under the control of the reciprocating valve-piston 11 influenced by compression of air in the engine cylinder, and is further controlled by oil pressure in the hollow valve rod and a spring 24 bearing on the 35 upper end thereof, with the tension of the spring regulated by an apertured plug 25 threaded into the upper end of a nipple 26 forming a connection with a fuel supply pipe (not shown). The nipple is suitably connected to the upper end 40 of the sleeve housing the valve rod, for which purpose the nipple and sleeve are provided with flanged lower ends.

In the operation of my improved injection valve the discharge of the fuel oil may be regulated in different ways, being effected by hydraulic pressure augmented by a spring in contradistinction to atmospheric pressure, to thereby obtain greater flexibility of operation, with the flexible hydraulic counterpressure regulated 45 in the usual manner by overflow valve, or any other well known means.

The operation is illustrated by the several views of the drawing, Fig. 1 showing the piston valve in the position before it has been actuated by the 55 pressure from the compression in the engine-cylinder, while Fig. 2 shows the position of said piston when the pressure is sufficient to lift the piston and valve stem and close the inlet openings 20 leading into the valve chamber, the noz- 60

zle being also closed; and Fig. 3 shows that the pressure has increased to such an extent as to open the needle valve for the injection of the fuel through the nozzle into the engine cylinder. It 5 is essential that the spring pressure on the valve rod be regulated with reference to oil pressure so as to close the valve at the proper moment, or when the piston of the engine passes the dead center, and to maintain said valve closed until 10 the operation is repeated.

From the foregoing it will be obvious that the operation of the injection valve is controlled by the compression in the engine cylinder to thereby provide a simple and effective means for supplying the fuel oil at the proper time, thus improving on the more expensive fuel injection pump and fuel injection valve commonly used in connection with internal combustion engines, and more especially with those of the Diesel engine 20 type—there being no need for driving mechanism, such as a cam, cam shaft, rollers, or other complicated mechanism for transfer of motion. My improved form of injection valve also dispenses with the need of any extra reversing means, and 25 by its use there is a uniform injection for the reason that the pressure rises in proportion to the pressure transmitted to the valve piston directly from the compression of air and fuel in the engine cylinder. Furthermore, the injection 30 valve, in accordance with my invention, is usable either in the cylinder head for two or four-cycle internal combustion engines, or in the side wall of the cylinder in connection with opposed piston internal combustion engines, obviating the necessity of fuel injection timings, and obtaining a 35 better mixture from the movement of the nozzle carried by the reciprocating valve-piston.

Another advantage of my improved construction of injection valve is the protection it provides 40 in the use of high fuel pressure, for in case the needle valve is clogged, or in the event of other slight defect, the pump supplying the fuel oil is adjusted to correct position automatically according to the compression in the engine-cylinder, 45 and is likewise adjusted in response to variable barometer pressure. As the valve is operated entirely by the compression in the engine-cylinder it follows that when the pressure rises to a predetermined point immediately before the engine-piston reaches dead center on its compression 50 stroke the needle valve is opened and when the engine-piston passes the dead center said needle valve is closed, and for a better understanding of 55 the operation of the valve the graph, Fig. 4, indicates its functioning— Z^1 and Y^1 representing the full stroke and X^2 and Y^2 a shorter stroke.

Although I have described my invention as especially adapted for use in connection with a two-cycle engine it will be understood that its 60 application may be extended to four-cycle engines in which an injection valve of this character can be employed for supplying fuel to the combustion chamber of the engine cylinder.

It will be obvious, from the foregoing description, that my improved injection valve operates automatically under mechanical and hydraulic influence, the springs balancing the compression pressure and amount of oil injected, for the reason that the strokes of the engine piston depend 70 on the pressure in the oil line regulated by the

usual governor (not shown) acting on the needle valve. When the valve in the oil line closes a little under the influence of the governor the pressure on the needle valve is less and allows the valve to stay open longer. Conversely, when the valve in the oil line is opened by the governor the pressure rises and acts on the top part of the needle valve to keep said valve open a shorter time. 5

This application is a division of my original 10 application for patent entitled "Improvements in internal combustion engines," filed August 31, 1936, Serial No. 98,775.

I claim:

1. An injection valve for internal combustion 15 engines comprising a reciprocating piston working in a cylinder and actuated in one direction by compression within the engine cylinder, a spring actuating the piston in opposition to the compression, said piston having a recess extending into the same to near its outer end, and a nozzle in the outer end of the piston communicating with the recess and engine cylinder and having a valve seat at its inner end; together with a sleeve or stationary valve casing extending into 20 the recess in the piston and terminating to form a fuel compression chamber intermediate the end of said valve casing and nozzle, a hollow fuel conducting piston rod extending through the valve casing and having a valve head at its outer end 25 adapted to seat on said valve seat, the passage in the hollow piston rod communicating with ports discharging into the fuel compression chamber above the valve head and adapted to be closed by the lower end of the sleeve or valve 30 casing, and a spring cooperating with the oil pressure to maintain the needle valve closed during the operation of the valve piston preliminary to the opening of the valve. 25

2. An injection valve for internal combustion 40 engines comprising a reciprocating piston working in a cylinder and actuated in one direction by compression within the engine cylinder, a spring actuating the piston in opposition to the compression, said piston having a recess extending into the same to near its outer end, and a nozzle in the outer end of the piston communicating with the recess and engine cylinder and having a valve seat at its inner end; together with a sleeve or stationary valve casing extending 45 into the recess in the piston and terminating to form a fuel compression chamber intermediate the end of said valve casing and nozzle, a fuel conducting hollow piston rod extending through the valve casing and having a valve head at its 50 outer end adapted to seat on said valve seat, the passage in the hollow piston rod communicating with ports discharging into the fuel compression chamber above the valve head and adapted to be closed by the lower end of the sleeve or valve casing, a spring bearing on the upper end of the piston rod and cooperating with the oil pressure to maintain the needle valve closed during the operation of the valve piston preliminary to the opening of the valve, said spring being located 55 in a tubular member connected to the aforementioned valve casing, and an apertured plug threaded in the tubular member to regulate the tension of the spring acting on the valve rod. 60
